UNITED STATES PATENT OFFICE.

EDWARD BORNHOEFT, OF NEW YORK, N. Y.

PIANO PEDAL-ACTION.

SPECIFICATION forming part of Letters Patent No. 792,192, dated June 13, 1905.

Application filed February 25, 1905. Serial No. 247,219.

To all whom it may concern:

Be it known that I, EDWARD BORNHOEFT, a citizen of the United States, residing at New York city, Bronx, county and State of New York, have invented new and useful Improvements in Piano Pedal-Actions, of which the following is a specification.

This invention relates to a piano pedal-action, and more particularly to simple and reliable means for operatively connecting the pedal-lever to the lifter-rod.

In the accompanying drawings, Figure 1 is a front view of my improved piano pedal-action; Fig. 2, a plan thereof with the piano-case partly in section and the lifter omitted; Fig. 3, an enlarged plan of the lifter-supporting end of the pedal-lever; Fig. 4, a section on line 4-4, Fig. 3, with the lifter in position; and Fig. 5, a front view of Fig. 3 with the lifter in position.

The letter A represents the front of a piano-case, and A' is the bottom thereof. The metal pedal-lever B is T-shaped in cross-section, being composed of a horizontal base *b* and a vertical web *b'*, projecting upwardly from the base. The lever B is mounted upon a spring *c* and is actuated by a pedal *d*, to which it is connected at one end by a bolt *d'*. At its op-

posite end the base *b* projects beyond the web *b'* to form a foot or flange *b''*, Fig. 4. Above 30 this flange there is secured to the lever B a strap composed of a ring-shaped body *f* and a pair of parallel shanks *f'*. These shanks straddle the end of web *b'*, to which they are riveted at *f''*. The ring *f* is thus secured in 35 position directly above flange *b''*, in conjunction with which it forms a socket or cup. This cup is provided with a bushing *b'''* and receives the lower end of the lifter-rod *g*, bushed at *g'*, the rod being thus connected to the pedal- 40 lever in a simple and reliable manner.

What I claim is—

In a piano pedal-action, a lever composed of an upright web and a horizontal base projecting beyond the web to form a flange, combined with a curved strap above the flange and having a pair of parallel shanks that are secured to the web, and a lifter engaged by the strap, substantially as specified. 45

Signed by me at New York city, New York, 50 this 24th day of February, 1905.

EDWARD BORNHOEFT.
